SPACE DISCHARGE TUBE

Howard E. Ackman and Emmett Finley Carter,
Emporium, Pa., assignors to Hygrade Sylvania
Corporation, Salem, Mass., a corporation of
Massachusetts

Application April 25, 1935, Serial No. 18,115

17 Claims. (Cl. 250—27.5)

This invention relates to space discharge tubes, and with particularity to an improved form of electrode support for discharge devices having a filamentary member.

5 In certain types of space discharge tubes, such for example as electron discharge tubes ordinarily employed in radio receiving and transmitting apparatus, it is customary to provide means to support and space a plurality of electrodes in such a way that the electrical and mechanical characteristics are not disturbed by mechanical vibrations or the like. This is particularly true in the case of those devices employing a filament which is adapted to act either as a heater member or as an electron emitter. In tubes employing a filament of V-shaped or similar configuration, means are usually provided to maintain the filament taut, especially when the filament is at its relatively high operating temperature. Many 10 methods of supporting such filaments have been proposed, but the most common one employs a tension hook or spring which engages the bight of the filament. While these metallic spring supports have advantages, nevertheless in certain 15 types of tubes the use of a metal spring support for the filament, is undesirable. One of the most serious draw-backs to the use of filament tensioning springs is the fact that when the filament is at its operating temperature the heat is unavoidably conducted to the spring which, after a period of use, tends to lose its resiliency and therefore its effectiveness in tensioning the filament. Another disadvantage of metal springs is that the filament hook must be of relatively 20 small mass where it engages the filament, thus necessitating a sharp bend in the filament with the consequent liability to rupture at the bend. A still further disadvantage of the metal hook type of filament support is that it is very difficult 25 to provide a spring or hook which is resilient along only one axis, with the result that while the filament may be kept under the proper tension longitudinally, it may vibrate bodily in a lateral direction thus changing the electrical 30 characteristics of the tube. Added to these disadvantages is the liability to production of microphonic noises by reason of the metal-to-metal contact between the filament and the metal hook, and the fact that the spring or hook may have 35 a natural period of vibration within a frequency range which is detrimental to the operation of the tube.

Accordingly, one of the principal objects of this invention is to provide an improved means 40 for supporting a heatable filamentary member

whereby the above-noted and other disadvantages are overcome.

Another object of the invention is to provide a novel form of insulator spring member for resiliently supporting a filament or the like.

A feature of the invention relates to an insulator member which serves the double purpose of accurately spacing a plurality of electrodes from each other while maintaining one of the electrodes under tension.

Another feature relates to the means for supporting a filament in a space discharge tube so that the legs of the filament are uniformly spaced apart.

Another feature of the invention relates to an improved arrangement including a resilient hook for tensioning a filament and means for preventing the hook from twisting the filament out of its normal planar shape.

Other features and advantages not specifically 20 enumerated will be apparent after a consideration of the following descriptions and the appended claims.

While the invention is of prime importance as applied to electron discharge devices such as radio 25 tubes or the like, it will be understood that it is equally well applicable to other types of devices employing a heatable filament which is required to be kept under tension. Therefore, while the drawings show the invention embodied in one 30 specific type of radio tube structure, it will be understood that this is done merely for purposes of explanation and not by way of limitation.

In the drawings, Fig. 1 illustrates in vertical section a radio tube mount embodying features 35 of the invention.

Fig. 2 is a top plan view of the mount of Fig. 1.

Fig. 3 illustrates a modification of the invention.

Figs. 4, 5 and 6 show another embodiment of the 40 invention.

Referring more particularly to Fig. 1, the numeral 1 represents in dotted outline one well-known form of enclosing envelope such as is employed in present day radio tubes. The envelope is sealed to a reentrant portion 2 terminating in a press 3 wherein are sealed the various lead-in and support wires 4 to 10 inclusive. Supported on the wires 4 and 10 is a tubular metal electrode 11, and supported on the wires 5 and 9 is a grid electrode comprising a pair of side rods 12, 13, around which is helically wound the fine grid wire 14 the individual turns of the wire 14 being fastened in any suitable manner to the side rods 12, 13.

The filament 15, which may be of an inverted U or V-shape, has its free-ends anchored, as by welding, to the wires 6 and 8, and for the purpose of supporting and spacing the electrodes apart there are provided a pair of insulator discs 16, 17. These discs may be made of any suitable insulating material but preferably are of mica and each mica disc is provided with a set of aligned perforations to receive the wires 4, 10 and the grid side rods 12, 13. The insulator discs may be held in place on the wires 4 and 10 by small lugs 18, welded to the said wires although any other similar method of fastening the discs in place may be employed. The lower mica disc 16 is provided with a slot 19 to allow the filament 15 to pass therethrough, while the upper mica disc 17, as shown in Fig. 2, is provided with an opening 20 and with an integral tongue 21. Tongue 21 is preferably, although not necessarily, provided with tapered edges 22, 23 to impart the desired degree of resiliency to the tongue. The forward corners of the tongue 21 are notched as indicated by the numerals 24 and 25 to provide recesses to receive the bight or bend 26 of the filament 15. Preferably the notches 24 and 25 are provided in alignment with the perforations in the disc 17 so that when the filament embraces the tongue 21, it is in planar alignment with the wires 4, 10, 12, 13. Preferably the filament 15 is so bent that the width of the bight is substantially the same as the width of the notched portion of tongue 21. With this arrangement the filament may be kept under the desired degree of the longitudinal tension because of the cantilever spring action of the tongue 21. However, the filament is prevented from swaying or vibrating in a lateral direction because of the substantial lateral rigidity of the tongue 21. While, in order to facilitate assembly, it is preferred to provide the forward end of the tongue 21 with oppositely disposed notches 24, 25, to receive the filament bight, if desired the tongue 21 may be provided with oppositely disposed slots or perforations through which the opposite legs of the filament pass. However, it has been found that if the lateral edges of the notches 24 and 25 are slightly inclined as shown in Fig. 2, it is not necessary to employ slots or perforations to maintain the filament in position. If the mica disc 17 is of too great a thickness to provide the required degree of resiliency to the tongue 21, this tongue may be scored or otherwise weakened as indicated by the dotted line 27. It will thus be apparent that because of the relatively large area of the tongue 21 considerable damping effect is provided to off-set any tendency of the filament to vibrate microphonically and the tongue 21 may be designed so that its natural period of vibration will be lower than any frequency which will be detrimental to the operation of the tube.

It will be understood of course that while the invention has been described in connection with an inverted U or V shape filament any other well-known form of filament may likewise be supported by the disc 17, and furthermore while a tube of the three element type as shown, it will be understood that a greater or less number of electrodes may be employed. Furthermore while the drawings show the tongue 21 as supporting a filament of the coated type, it will be understood that the invention, if desired, may be employed in supporting the heater wires of so-called indirectly heated cathodes. It will also be understood that the method of supporting the various electrodes from the press of Fig. 1 is merely illustrative and

that any other well known manner of support may be employed.

In certain cases it may be desirable to support the filament so that the side legs thereof are substantially parallel. Thus as illustrated in Fig. 3 the filament 15 is supported at its upper end by means of an insulator disc 28 having a notched tongue 29 similar to the tongue 21 of Figs. 1 and 2. The lower disc 30 instead of being provided with a slot like the slot 19 of Fig. 1, is provided with a tongue 31 similar to the tongue 29. In this embodiment the free-ends of the filament 15 are preferably fastened to the support wires 6 and 8 so that the lower portions of the filament legs are in engagement with the edges of the notched portions 32 and 33 which notches correspond to the notches 34, 35 in the top disc 28 and also to the notches 24 and 25 of the upper disc of Figs. 1 and 2. For the purpose of simplicity the remaining electrode or electrodes of the tube and the remaining parts of the mount are omitted from Fig. 3 it being understood of course that the discs 28 and 30 are supported in spaced relation to each other in any well known manner.

In certain instances it may be preferable to employ the tongued mica above described merely for the purpose of spacing the legs of the filament apart while employing an ordinary resilient metallic hook to maintain the filament taut. Thus there is shown in Fig. 4 a preferred form of tube structure which has been found to produce the desired results. In this figure the numeral 36 indicates in dotted outline, one well-known form of enclosing bulb having integrally attached thereto a reentrant stem 37 terminating in the press 38. Sealed into the press 38 are the lead-in and support wires 39 to 46 inclusive. Fastened to the wires 39 and 43 is a tubular metal plate or anode 47 which may be cylindrical in shape. Mounted adjacent the upper and lower edges of the anode 47 are insulator discs 48, 49 of mica or other suitable insulating material. These discs may be held in place against the edges of the anode by suitable lugs or swaged portions 50 on the wires 39 and 43. The discs 48 and 49 may be of any desired shape but are preferably both of the same shape as shown in Fig. 5 of the drawings. The lower disc 49 is provided with a slot through which pass the two legs of the filament 51. The free ends of the filament are welded to the filament support wires 41, 46 while the filament is maintained under vertical tension by means of a resilient metal hook 52 which may be welded to the upper end 53 of the support wire 42 as shown in detail in Fig. 6. For the purpose of spacing the upper portion of the filament legs apart, and for insuring that the hook 52 does not distort the filament out of its planar shape, the upper disc 48 is provided with a tongue 54 similar to the tongue 21 of Figs. 1 and 2. In this embodiment however the tongue 54 is not relied upon to provide the tension for the filament, but is used merely to space the legs of the filament apart and to prevent the hook from distorting the planar shape of the filament while it is under tension. It has been found however, that by interposing the mica tongue 54 between the filament and the hook the said hook can be maintained at a sufficiently low temperature to prevent its losing its springiness. In the particular tube illustrated, the filament 51 is surrounded by a series of grids 55, 56, 57 and 58. Each of these grids may consist of a pair of metal uprights around which is helically wound a fine grid wire preferably with each of the grid

wire turns welded or mechanically fastened to the vertical support wires, and in order to insure the proper spacing of the electrodes the grid support wires register with corresponding perforations in the discs 48, 49, as shown clearly in Figs. 4 and 5 of the drawings. Interposed between the grid 55 and the grid 56 are a pair of metal strips 59, 60, these strips being united at their lower ends by the metal strap 61 which is of course curved so as to clear the legs of the filament, and the remaining electrode support wires. The upper ends of the strips 59 and 60 register with corresponding slots in the upper disc 48 as shown clearly in Fig. 5 of the drawings. When the device of Fig. 4 is to be used as a frequency converter or oscillator modulator, the filament or cathode 51 in conjunction with the grid 55 and the strips 59 and 60 may form together with a suitable feed-back circuit arrangement (not shown) an oscillator, so that the potential of grid 55 varies in a regular manner at the desired frequency under control of the oscillatory circuit. The grid 56 may have a suitable positive potential impressed thereon with respect to the filament or cathode so that it acts as an accelerating grid for the electrons emitted from the cathode. In effect therefore the grid 56 may be considered as the virtual cathode for the remaining electrodes of the tube, that is for the grid 57, grid 58 and the main anode 47. When the device is used for a frequency converter or oscillator modulator, the grid 51 may be considered as the control grid in the sense that it modulates the electron stream from the virtual cathode formed by the grid 56 as described above and for this purpose a separate lead-in wire 62 may connect the control grid 51 preferably with the metal top cap 63. The grid 58 may be connected by the strap 64 to the accelerating or virtual cathode grid 56 and when a suitable positive potential is applied to the grid 58, it will act as a screen or shield grid to screen the control grid 57 from the fluctuations of potential on the anode 47.

While the embodiment of Figs. 4, 5 and 6 shows the tongued mica in a tube of the pentagrid type, it will be understood that it can be equally well applied to any other type of tube employing a filamentary heater or cathode.

Various changes and modifications may be made in the particular embodiments disclosed without departing from the spirit and scope of the invention.

What is claimed is:

1. In a device of the character described, a filamentary member, means to anchor said member at one end, and means to support said member resiliently at the other end, the last mentioned means including a flexible tongue consisting of insulation material and engaging said filamentary member.
2. In a device of the character described, a pair of filament sections, means to anchor said filament sections at one end, and means to support said sections resiliently at the other end, the last mentioned means including a flexible flat tongue consisting entirely of insulation.
3. In a device of the character described, a filament, means to anchor said filament at one end, and means to support said filament resiliently at the other end, the last mentioned means including an insulator strip provided with a cut-out portion and a flexible tongue of insulation associated with said cut-out portion.
4. In a device of the character described, a fila-

mentary member, means to anchor said member at one end, and means to support said member resiliently at the other end, the last mentioned means including a flat tongue of insulation flexibly supported at one end and having at its other end cut-out portions in its edges to form a pair of oppositely disposed notches to receive the filament.

5. In a device of the character described, a filament and means for maintaining the filament under tension comprising a mica tongue flexibly supported at one end, and having a filament engaging portion at the opposite end.

6. In a device of the character described a filament, an electrode cooperating with said filament, an insulator spacer disc for insulatingly spacing said filament and electrode, said disc having a cut-out portion to form a free-ended insulator tongue to engage the filament to maintain it in vertical alignment.

7. In a device of the character described a filament having a bight, an electrode cooperating with said filament, a disc of insulation supported adjacent the bight of said filament and the end of the electrode, said disc having a cut-out portion defining a flat tongue, said tongue having a plurality of notches to engage the filament bight.

8. In a device of the character described a filament, an electrode surrounding said filament, means to support said filament and electrode at one end, insulator spacer means for spacing the filament from the electrode at the other end, said spacer means having an opening to receive the filament and being provided with an integral flexible tongue of flexible insulation in said opening and engaging the filament to maintain it in axial alignment with said electrode.

9. A tensioning device for a filamentary electrode having a bight comprising a tongue of insulation flexibly supported at one end and having its other end cut-out to form a pair of notches to receive the legs of the filament adjacent the bight thereof.

10. A combined electrode spacer and filament aligning member for space discharge tubes comprising a disc of insulation having a cut-out portion to receive a filament bight and having perforations to receive electrode support rods, said cut-out portion being provided with a struck out portion to form an integral flexible tongue of insulation to engage the filament adjacent the bight thereof.

11. A combined electrode spacer and filament aligning member for space discharge tubes comprising a mica disc having a portion struck out therefrom forming an integral flat tongue, said tongue having a portion adapted to engage the bight of the filament.

12. A combined electrode spacer and filament tensioning member for space discharge tubes comprising a disc of mica provided with a cut-out central portion, a plurality of aligned perforations to receive electrode support rods, a flat resilient tongue in said opening said tongue being provided with notches in alignment with said perforations said notches adapted to receive the filament.

13. A filament tensioning member for electron discharge tubes comprising a mica tongue having appreciable flexibility in the direction in which the filament is to be tensioned and being substantially rigid in a transverse direction.

14. In a device of the character described a pair of filament sections having a bight portion, and means to space said filament sections and to maintain them under tension, said means includ-

ing a mica tongue inserted between the sections of the filament adjacent the bight to maintain said sections in planar alignment.

15. A device according to claim 14 in which the tongue is integrally formed from a cut-out portion of an insulator member which serves to space the filament sections from the remaining electrodes of a device, and the tension device in the form of a spring hook engages the filament bight.

16. An electrode spacer member for radio tubes

comprising a disc of insulation having a central struck out portion to provide an integral filament alignment tongue, and having a plurality of perforations to receive electrode support wires.

17. An electrode spacer member for radio tubes comprising a mica disc having a substantially U-shaped struck out portion to form an integral flat flexible filament aligning tongue.
